UNITED STATES PATENT OFFICE

2,438,557

ELECTRIC DISCHARGE DEVICE

Theodorus Hehenkamp, Eindhoven, Netherlands,
assignor, by mesne assignments, to General
Electric Company, Schenectady, N. Y., a cor-
poration of New York

Application February 26, 1943, Serial No. 477,331
In the Netherlands December 10, 1940

Section 1, Public Law 690, August 8, 1946
Patent expires December 10, 1960

1 Claim. (Cl. 315—100)

1

In a device comprising an electric gas discharge tube (which term is here employed to refer not only to a discharge tube in which the discharge occurs in a filling constituted merely by gas, but also to discharge tubes comprising a vapor filling or a filling constituted by gas and vapor) furnished with two incandescent electrodes. One end of each electrode is connected in series with a contact of a bimetallic switch and the other end of each electrode, with the interposition of a choke coil respectively directly, with the terminals of the source of current. When the entire installation is energized the contacts of the bimetallic switch are closed so that a current is conducted in the choke coil and the incandescent electrodes. One of the connecting conductors between tube and source of current includes the heating element of the bimetallic switch so that the contacts of the switch open after a lapse of a predetermined interval of time and the choke coil induces a potential pulse which assists in initiating an arc discharge in the tube. If initiation of the discharge occurs the bi-metallic switch is maintained open by the heating element but in the case of misfiring the bi-metallic switch closes again and the starting system attempts a re-cycling operation.

In this starting device the disadvantage exists that if the discharge tube is defective the automatically operating starting system continues to operate without the possibility of an arc discharge occurring. This not only may lead to damage of the starting device and circuit therefor but also may result in overheating the choke coil. This necessitates a choke coil of larger dimensions than those required for normal use or else assumes the risk that the choke may likewise be caused to deteriorate.

In addition, if this device is supplied with alternating current other effects may also be responsible for the occurrence therein of currents of inadmissibly high intensity. The originally equal emitting power of the electrodes may have changed, for example by the end of the life of the tube, in such a manner that in a given half-cycle of the alternating-current-supply the current is considerably lower than in the next-following half-cycle. This involves the occurrence of a direct-current component with the result that the choke exhibits a lower impedance than if an alternating current without direct-current component is conducted therein. Hence, the choke gives passage to a larger current with the result that it is subjected to intenser heating than in the normal use of the tube.

2

It is obvious that a current of undesired strength due to the occurrence of a direct-current component may occur even in the absence of an automatic ignition or starting system.

5 Similar difficulties may also exist in other devices in which a discharge tube is likewise connected in parallel with part of a circuit connected to the source of current. Thus, for example, devices are known which include a resonance circuit constituted by the series combination of inductance and capacitance, the discharge tube being connected in parallel with the inductance or with the capacitance and comprising an incandescent electrode which is included in the 10 resonance circuit. When such device is connected in the circuit the resonance circuit has passing through it a large current which causes the said incandescent electrode to assume the emission temperature and sets up high voltages 15 between the ends of the inductance and between the condenser electrodes. The discharge tube, after an arc discharge occurs, forms a parallel branch conductor with part of the resonance circuit with the result that the current strength 20 in this circuit falls off considerably.

This device also presents the disadvantages heretofore mentioned, since if an arc discharge does not occur in the discharge tube for any reason whatsoever there is the risk that the 25 elements of the device may be caused to deteriorate, as in the case of the occurrence of a direct-current component.

30 My invention relates to a device comprising an electric gas-discharge tube and a branch conductor in which, due to misfiring of the tube or as a result of the occurrence of a direct-current component when the tube is in use, a current 35 may be conducted which is inadmissible on account of its value and/or duration and it has for 40 its object to avoid damage of the elements of the device.

According to my invention, I provide a means 45 which, when the said inadmissible current occurs, applies such a high voltage to a bridge whose interruption throws the device out of action, this bridge having passing through it a current of higher intensity than the inadmissible current and is interrupted thereby.

According to my invention, I have found that 50 it is impossible or else extremely difficult to construct a cut-out or other kind of almost permanently interruptible bridge, for example a magnetically operating switch, which is interrupted by the current of undesired strength that occurs 55 in defective tubes. The following effects may be

mentioned as responsible for the difficulties thereby incurred: the inadmissible currents are often not much greater than the normal operating current in the branch conductor concerned. In addition, the supplementary voltage which occurs in the case of potential fluctuations of the current supply is substantially effective in that part of the circuit which is located outside the discharge tube and hence also in the cut-out. Further, it is not immaterial in what surroundings the cut-out has to operate, for example in a room with slight temperature differences in regard to the mean temperature prevailing there or in the open air where, apart from great temperature differences, it may be exposed to the influence of wind and rain. It is hardly possible for the supplier of the device previously to take these conditions into account. In devices in which starting the discharge tube is brought about by automatically operating ignition or starting systems the current occurring prior to starting is often greater than the operating current with an inadmissible direct current-component; nevertheless, it must be possible for this large starting current to be maintained for a certain length of time, for example at least until the electrodes of the discharge tube have assumed the emission temperature. According to my invention the difficulties outlined are avoided by providing a means whereby the bridge is not interrupted by the undesired current itself but by a current which may be made much larger and which, as a result of the said high voltage at the bridge, starts to flow through the latter. This results in the disposition of the bridge being also independent of the branch conductor in which the undesired current occurs so that the device can be thrown out of action by the interruption of only one bridge, even if undesired currents may be expected in more than one circuit.

Such is the case in devices in which the discharge path of the gas-discharge tube is connected in parallel with part of a circuit connected to the source of current and in which a high voltage is automatically set up for starting the discharge tube. In the case of misfiring of the tube, a large current of unduly long duration occurs in the starting circuit whereas a direct current component appears in the supply leads of the tube.

According to my invention, in this device the bridge may be included in that part of the connecting lead between the discharge path of the tube and the source of current which is also included in the starting circuit.

In devices comprising gas discharge tubes the discharge tube may often be spaced a large distance from the voltage-drop impedance or other elements of the device so that in replacing the defective tube and repairing or replacing the interrupted bridge there would be the need to work at two different points.

According to my invention this is improved by incorporating the bridge between the discharge path and a connecting contact of the tube. The bridge being thus integral with the discharge tube, the tube which no longer operates normally and is therefore valueless anyhow is rendered unserviceable without any damage to other elements of the device so that upon replacement of the defective tube the device is again in readiness for operation.

Due to the fact that the invention permits of employing a larger current than the undesired current for the interruption of the bridge, an incandescent electrode of the tube provided with

two supply wires may act as the bridge. To interrupt such bridges, voltages lower than the network voltage generally suffice. These voltages may be tapped off at suitably chosen points of the device or the network voltage may be lowered by a transformer or via potentiometers or voltage-drop impedances. For higher voltages than the network voltage use may be made of step-up transformers or other voltage-increasing means.

10 In the case of bridges arranged in the discharge space of the gas-discharge tube, for example in the case of incandescent electrodes, an arc discharge may occur upon interruption of the bridge, in parallel with the aperture then formed in the bridge and re-close the circuit. In order that in such cases the circuit will definitely be interrupted, the bridge according to my invention may comprise a cut-out located outside the discharge space.

20 According to my invention, the means that cause the requisite voltage to be effective in the bridge may be constituted by at least one thermal switch, for example a bimetallic switch, whose heater is included in the operating circuit of the tube and/or in that part of the circuit setting up the starting-up voltage which is connected in parallel with the discharge path.

25 Thermal switches have the property of becoming operative at a greater or lesser speed according to the value of the current passing through the heater and of not coming into play below a minimum current intensity. The heater for such switches may be constituted by impedances, for example chokes, condensers, and/or resistances through which the undesired current passes.

30 In a number of devices the high current values necessary for starting up occur in the same branch conductor as that in which also currents of undesired strength may occur as a result of a direct-current component so that in such devices the use of a single means is sufficient. In devices 35 having diverting properties it is preferable that special means should be provided at suitable points for any effect responsible for unduly high currents, it being often possible to use a far-reaching combination of the means.

35 In order to spare the heater of the thermal switch it may be arranged in such manner that it is not included in the circuit which comprises the contacts of the switch.

40 In order that my invention may be clearly understood and readily carried into effect it will now be described more fully with reference to the accompanying drawing in which:

45 Figure 1 illustrates a circuit arrangement in accordance with the invention.

50 Fig. 2 illustrates another embodiment of the invention and

55 Fig. 3 illustrates a further embodiment in accordance with the invention.

60 Fig. 1 shows a device comprising a discharge lamp 1. This lamp may be of well known construction and may constitute, for example, a low pressure mercury-vapour discharge tube 65 whose wall is provided with substances that become luminescent under the influence of the discharge. The lamp 1 comprises two incandescent cathodes 2 and 3 coated with substances which will copiously emit electrons and caps 4 and 5 at the ends of the tube. The electrode 2 is connected on the one hand via a ballast or choke 6 to the terminal 7 of a source of alternating current and on the other hand to the electrode 8 of an auxiliary discharge tube 9, where 70 as the electrode 3 is connected on the one hand 75 to the terminal 10 of the source of alternating current.

via an over-load cutout 10 incorporated in the cap 5 to the terminal 11 of the said source of current and on the other hand to the electrode 12 of the tube 9. The auxiliary tube 9 comprises a gas filling, for example neon, at a low pressure, for example of 10 mms. of mercury, and the electrodes 8 and 12 are constituted by bimetallic strips which engage each other under the influence of the heat evolved by the discharge. The tube has such dimensions that it will operate at the full network voltage but will not operate at the operating voltage of the main discharge tube 2 at its electrodes.

The device operates as follows:

Upon connection of the device to the source of current via a switch (not shown) the voltage of the source of current is effective between the electrodes 8 and 12 of the auxiliary discharge tube 9. A glow discharge occurs in tube 9 and the electrodes 8 and 12 engage each other after a short time with the result that the electrodes 2 and 3 of the main discharge tube 1 have passing through them a large current which is only limited by the ballast or choke 6 and causes them to assume the emission temperature very quickly. Since the electrodes of the tube 9 have no longer heat supplied to them, the bimetallic strips cool and the electrodes are again disengaged, the circuit being thereby interrupted and a high voltage serving for starting up the lamp 1 being generated in the choke 6.

When the lamp 1 is started, the full network voltage is no longer applied to the electrodes of tube 9 but only the operating voltage of lamp 1 so that the discharge in tube 9 is no longer initiated and the contact between 8 and 12 continues to remain in its normally open position.

In the case of misfiring of lamp 1, the ignition or starting system starts a re-cycling operation. Should the lamp give out after repeated starting attempts there is the risk that choke 6 may deteriorate due to a large current that exists with short-circuited electrodes 8 and 12.

To avoid this, the choke 6 is provided with a bimetallic strip 13. This strip is connected to that end of the electrode 3 which is connected to the electrode 12 and is constructed so that on the choke assuming a certain temperature the contact piece 14 engages the contact piece 16 which is connected to a tapping 15 of the choke.

In the case of misfiring of the lamp 1, so that the network voltage, only reduced by part of the choke 6, becomes effective in the electrically conductive bridge of the lamp 1, which is constituted by the electrode 3 and the cut-out 10 connected in series with each other, this bridge has passing through it a very large current which brings about blowing of the cutout 10 with the result that the ignition system is thrown out of action.

Excessive heating of the choke 6 may also occur if the electron-emitting power of one of the electrodes of the lamp 1 falls off. This may be due to the electrode concerned becoming bald, that is to say that the emitting material disappears from the core of the said electrodes. Due to this phenomenon less current passes through the discharge tube in the half-cycle in which the poorly emitting electrode acts as the cathode as compared with the half-cycle within which the properly emitting electrode acts as the cathode. As previously mentioned, this involves the occurrence of a direct-current component as addition to the alternating current with the result that

the choke on which magnetization is superposed by direct current allows the passage of more current than without direct-current component.

In this case also the bimetallic strip will bridge the points 14 and 16 and bring about the interruption of the bridge 3-10 as soon as the temperature of the choke 6 assumes a predetermined temperature. This ensures that the device is undamaged and the defective tube alone deteriorates.

In a number of cases the bridge to be interrupted depends upon the disintegration or destruction of electrode 3 alone which in such a case must have such dimensions as to blow upon engagement of the contacts 14 and 16. This, however, gives rise to the possibility of a discharge occurring between the ends of the electrode 3 which are located within the discharge space of the tube, which would result in the circuit that was interrupted by the rupture of the electrode 3 being closed again.

Here, the use of the cut-out 10 outside the discharge space of the tube offers a solution. The large current set up by the increased voltage passes through the cut-out 10 in any case irrespective of the occurrence or non-occurrence of a discharge between the ends of the electrode.

By the way of illustration it may be mentioned that in one concrete case the normal current-strength of the discharge tube 1 was 250 ma., whereas the electrodes 2, 3 while being heated up had passing through them a current of 450 ma., it being possible for the discharge current in the presence of a direct-current component to be 350 ma.

The arrangement of the cut-out in the common part of the supply circuit and the starting circuit of the tube 1 ensures that upon blowing of the cut-out 10 the tube 1 is thrown out of action under any conditions.

Fig. 2 shows a device comprising a discharge lamp 17 which may be, for example, an elongated low-pressure metal-vapor discharge tube. The tube contains singly heated incandescent electrodes 18 and 19. Laterally of the electrode 18 a cut-out 20 is arranged in the cap of the tube (not shown) outside the discharge space of the lamp and connected in series with the electrode 18. This fuse is included in the common part of the supply circuit and the starting circuit of the tube.

The electrically conducting bridge of the lamp 17 which is constituted by the members 18 and 20 is included in a circuit which is connected to the terminals 21 and 22 of the source of alternating current and which is constituted by chokes 23, 24 and a condenser 25 connected in series with each other. The two chokes 23 and 24 are generally arranged on a common iron core. The incandescent electrode 19 is connected, with the interposition of a choke 26, to the choke 23 and the condenser 25. This incandescent electrode is heated in a manner not indicated in further detail by a current which is substantially equal to the heating current of the incandescent electrode 18 and for this purpose may be coupled to the circuit of the electrode 18 for example by means of a transformer. Alternatively, it is possible for the electrode 19 to be heated in series with the electrode 18 in that the connection between the condenser 25 and the point intermediate the chokes 23 and 26 is removed and the choke 26 is provided with an auxiliary winding which interconnects the free ends of the electrode 19 and the condenser 25 and is wound in such manner that when a

series current passing through both windings of the choke, magnetic fields counteracting each other are set up.

The device shown operates as follows:

When the device is energized the circuit constituted by the series connection of the choke coil 23, the condenser 25, the bridge 18-20 and the choke coil 24 is connected across the source of alternating current 21-22. The inductance of the chokes 23 and 24 and the capacitance of the condenser 25 are so proportioned that between the condenser electrodes a voltage occurs which causes the electrodes of the tube to assume the emission temperature. After an arc discharge has occurred in tube 17, tube 17 forms a shunt across the condenser 25 so that the voltage across the terminals of the latter decreases. At the same time, the current which flows through the series connection of the chokes and the condenser also decreases so that the incandescent electrode 18 which at this point is also heated by the discharge current also has a smaller current passing through it. The discharge current flows towards the tube 17 via the chokes 23 and 26 on the one hand and the choke 24 on the other hand.

In the case of misfiring of the tube 17 the condition of high voltages and large current would subsist. The occurrence of a direct-current component will likewise cause a large current to be set up in the circuit of the discharge tube. In both cases the current strength is higher than in the normal operating condition so that the device is likely to be damaged.

To avoid this the heater 27 of a bimetallic switch is included between the choke 23 and the terminal 21 of the source of current. Starting with a given current strength which is obviously higher than the normal current strength at this point, the heater 27 causes the contacts 28 and 29 to engage each other. The contact piece 28 is connected via a bimetallic strip 20 to a point between the terminal 21 and the element 27, whereas the contact piece 29 is connected to a point between the condenser 25 and the electrode 28 so that the cut-out 20 is only connected to the voltage of the source of current 21-22 with the interposition of the choke 24 and the incandescent electrode 18. Obviously, it will be possible for this voltage at the cut-out 20 to be raised or lowered if necessary, with the use of well-known means.

In the case illustrated the heater 27 is so included in the circuit arrangement that the large current required for the interruption of the bridge 18-20 does not flow through the element 27 itself. Any damage of this element is thus avoided. As a matter of fact after the contacts 28, 29 have been closed the bimetallic switch has not supplied to it any further heat energy but in practically occurring cases the contacts are maintained closed for a sufficiently long time to enable the increased voltage to interrupt the bridge meanwhile.

In one concrete case, in a tube not yet started the voltage across the choke 23 was 60 volts; across the condenser 25, 360 volts; across the bridge 18-20, 12 volts; and across the choke 24, 100 volts, the current passing through the series circuit being 400 ma. With normally operating tube the current passing through the tube 17 and the choke 26 had an intensity of 250 ma., through the chokes 23 and 24, of 150 ma. and through the condenser 25, of 225 ma., the voltage across 23, 24, 25, 26 and 18-20 being respectively, 28, 48, 190, 150 and 2 volts. The bimetallic switch had such a characteristic curve that with a current

of 190 ma. through the heater 27 its contacts did not engage each other but at 350 ma. (direct-current component) in 14 seconds and at 400 ma. (non-igniting tube) in 10 seconds. The contacts 5 28-29 being closed, the current passing through the bridge was 1.5 amp. The interruption of the bridge ensued 7 sec. after the closure of the contacts 28-29. The source of current 21-22 was an alternating current network of 50 cycles and 10 a voltage of 220 volts.

Fig. 3 shows a device comprising a gas-discharge tube 50 which may be, for example, a sodium-vapour lamp and is provided with two incandescent electrodes 31 and 32. These electrodes are interconnected via a choke 33 and a condenser 34. The other end of the electrode 31 is connected via a ballast or choke 35 to the terminal 36 of a source of alternating current, and the other end of the electrode 32 via a cut-out 37 to the other terminal 38 of the source of current.

The inductances of the chokes 35 and 33 and the capacitance of the condenser 34 are such that at least when the electrodes have assumed the emission-temperature a voltage sufficient for the ignition of the discharge path of the tube 50 between the electrodes 31 and 32 occurs. After the discharge path has been ignited tube 50 forms a shunt across the series connection of the choke 33 and the condenser 34 with the result that the voltage between those ends of this series connection which are connected to the tube falls to the operating voltage of the tube and at the same time the high starting current passing through 35 33 and 34 similarly falls off considerably. In the case of misfiring of the tube the condition of high voltages and currents is maintained, whereas upon the occurrence of a direct-current component the current conducted in the choke 35 increases.

By way of illustration it may be mentioned that in one concrete case with a source of alternating current 36-38 of 50 cycles and a voltage of 220 volts the current passing with non-ignited tube through the series combination of the choke 35, electrode 31, choke 33, condenser 34 and bridge 32, 31 was 226 ma. With normally operating tube the current passing through the choke 35 was 225 ma., through the tube 50, 240 ma. and through the series combination of 33 and 34, 56 ma.

As revealed thereby, the device may be arranged in such manner that the current passing through the choke 35 is substantially independent of whether or not the tube is started. In contradistinction thereto the current passing through the members 33 and 34 connected in parallel with the tube is dependent on the ignition or non-ignition of the tube. It will, however, be clearly evident that the occurrence of a direct-current component increases the current passing through the choke 35.

The device shown therefore includes two bimetallic switches 39 and 40 for which the chokes 65 35 and 33 respectively serve as heaters. The two switches are adapted to connect the tapping 45 of the choke 35, via the contacts 41, 42 and 43, 44 respectively, to that end of the electrode 32 which is connected to the condenser 34 and thus to bring about interruption of the bridge 32-37 of the tube 30. The switch 39 operates upon the occurrence of a direct-current component and the switch 40 upon misfiring of the tube. The cut-out 37 is arranged in the common part of the supply-circuit and ignition or starting circuit of

the tube 50 where the current has practically the same value when the tube is in normal use as in the case of the tube not being started.

I claim:

In combination, a supply circuit, an electric discharge device having a pair of filamentary electrodes, a ballast connected between one terminal of said circuit and one of said electrodes, an over-load cut-out device connected in series relation with said device between the other terminal of said circuit and the other electrode, a glow discharge switch of the bi-metal type connected across said electrodes and completing a preheating circuit for said electrodes through which said electrodes are energized from said circuit in series relation with said ballast and said cut-out device, and a bridge circuit connected between said other electrode and an intermediate tap of said ballast and including a thermal device having normally open contacts and being responsive to the current conducted by said ballast

5

10

for transmitting current from said supply circuit in an amount sufficient to operate said cut-out device upon repeated attempts of said switch to initiate conduction by said discharge device.
